UNITED STATES PATENT OFFICE.

GEORGE S. SARGENT, OF CHICAGO, ILLINOIS.

PROPELLER FOR HELICOPTERS.

Application filed November 18, 1925. Serial No. 69,748.

The present invention has to do with aeronautics, and is particularly concerned with propellers for flying machines of the helicopter type.

5 The principal object of the invention is to provide an improved propeller which presents extensive surfaces for engagement with the air, and which, because of the arrangement, formation and movements of such surfaces, is capable of operating through the air with practically no relative slippage. While the propeller of the invention is primarily intended for use with helicopters, it is also susceptible of use with 15 other types of flying machines.

Another object is to provide an improved propeller which is light, strong and durable in construction, is compact in arrangement, and is highly efficient in operation.

20 Other objects and advantages not herein specifically referred to will be evident to those skilled in the art upon an understanding of the nature of the propeller; the invention residing substantially in the novel 25 formation, combination and arrangement of parts hereinafter described.

One form of the invention is presented for the purpose of exemplification, but it will be understood that the invention is not 30 limited in its numerous practical applications to the precise details of construction shown in connection with that form, as such details obviously may be modified in various ways without departing from the comprehensive scope of the invention as defined 35 in the appended claims.

In the accompanying drawings—

Fig. 1 is a diametrical section taken 40 through a propeller constructed in accordance with the invention;

Fig. 2 is a rear view of the propeller;

Fig. 3 is a side view of the outer section of the propeller;

Fig. 4 is a similar view of the middle section of the propeller;

Fig. 5 is a similar view of the inner section of the propeller; and

Fig. 6 is a typical section through any one of the propeller blades.

50 The propeller of the invention is of sectional construction, and includes an outer section 10, a middle section 11, and an inner section 12. The sections are of generally annular form, and are nested concentrically in lapped relation to each other, preferably with the outer section a little in advance of

the middle section, and the middle section in turn a little in advance of the inner section, all as shown in Figs. 1 and 2.

Each section consists of a frame work 60 13 of generally annular form to which a plurality of helical blades 14 are secured at regular intervals about the outer periphery of the same. The blades 14 are curved in cross section, as shown in Fig. 6, and 65 preferably are widened progressively from their entering edges 15 to their trailing edges 16. The trailing edges of the blades preferably are set away from the axis of the propeller a greater distance than the 70 entering edges, which arrangement renders the blades slightly spiral as well as helical relative to such axis. The frame work of each section is suitably stream-lined and may advantageously consist of a plurality of 75 connected ring members, the frame work of the middle section being of substantially cylindrical form, and the frame works of the inner and outer sections being of slightly conical form with the frame work of the 80 outer section tapering toward the front of the propeller and that of the inner section tapering toward the rear of the same.

The sections are adapted to be rotated at 85 high speed with the outer and inner sections moving in one direction and the middle section moving in the opposite direction, the speed of rotation for each section preferably being such relative to the other sections 90 as to give approximately the same linear speed to the entering edges of the blades of all of the sections.

The mechanism for rotating the sections will of course vary in character, depending upon the type of flying machine with which the propeller is to be used. If the propeller is to be used for instance with a helicopter, a mechanism such as shown in Fig. 1 may advantageously be employed. The mechanism therein shown includes a main operating shaft 17 which is positioned transversely in front of the propeller and carries three bevel gears which mesh with three similar gears connected with the sections. 100

The frame work of the inner section is supported from a hub 18 by means of a plurality of intervening spokes 19, and the hub 18 is secured to the rear end of a shaft 20 which seats at the front end thereof in a thrust-bearing member 21 journaled on a medial portion of the shaft 17. A bevel gear 22 is secured to the front end of the 110

shaft 20, and meshes with a relatively large bevel gear 23 which is secured to the shaft 17 at one side of the axis of the propeller.

5 A sleeve 24 is journaled on the shaft 20 between the hub 18 and the gear 22, and the frame work of the middle section is supported from a hub 25 which is secured to the rear end of the sleeve 24. A bevel gear 26 is secured to the front end of the sleeve 24, 10 and meshes with a bevel gear 27 of about the same size which is secured to the sleeve 17 on the other side of the axis.

15 The frame work of the outer section is supported from an outwardly grooved ring member 28 which is secured to the spokes 29 of that frame work between the same and a hub 30 carried by the spokes, which hub serves to position the inner and middle sections of the propeller by positioning the 20 sleeve 24. The ring member 28 turns freely in axially locked engagement with two oppositely disposed positioning shoes 31 which ride in the groove in the ring member and are carried by two supporting brackets 32 journaled on the shaft 17 at opposite sides of the axis of the propeller. A bevel gear 33 is provided on the front face of the 25 ring member 28, and such gear meshes with a relatively small bevel gear 34 which is secured to the shaft 17 at the same side of the axis of the propeller as the gear 23. The supporting brackets 32 are held against angular movement about the axis of the shaft 17, but may be adjusted angularly in 30 unison thereabout by any suitable means acting through two sleeves 35 to which the brackets are secured, in order to vary the position of the axis of the propeller, whereby the propeller may be set in a substantially vertical position for moving the associated helicopter vertically and then changed to a substantially horizontal position for moving the helicopter horizontally when elevated.

35 It will be evident from the construction above described that, when the shaft 17 is rotated, the gears 23, 27 and 34 thereon will rotate the gears 22, 26 and 33, and the sections of the propeller will be correspondingly rotated, the outer and inner sections being moved in one direction and the middle section being moved in the opposite direction.

40 In operation, the propeller of the invention is capable of delivering a strong and steady thrust, as it engages efficiently with all parts of the air column with which it comes into contact. In the operation of the ordinary propeller, however, a considerable amount of slippage and lateral dissipation in the air column is experienced because only the tips of the blades of such a pro-

55 peller engage to any extent with the air, and a substantial part of the air so engaged is deflected laterally toward or away from the propeller axis instead of being forced rearwardly. The shape and arrangement of the blades in the present propeller is such as to effect an extended screwing engagement with the air which to a large extent eliminates slippage and lateral dissipation of the air, owing to the formation and relative disposition of the nested sections and the transverse curvature and rearward diversions of the oppositely moving blades.

75 I claim:

1. A propeller, comprising three concentrically arranged outer middle and inner sections, each of which is set in advance of the inwardly adjoining section and is provided with a plurality of helically disposed blades which are concave in cross section and are widened progressively from their entering to their trailing edges, and means for 80 rotating the outer and inner sections in one direction and the middle section in the opposite direction with the entering edges of the blades of all of the sections moving at substantially the same speed.

85 2. A propeller, comprising a plurality of concentrically arranged sections, each of which is provided with a plurality of helically disposed blades, an operating shaft positioned transversely of the axis of the propeller adjacent one end of the same, bevel gears corresponding in number to the sections secured to the shaft, other bevel gears connected for rotation with the sections and meshed with the gears on the shaft, and means for varying the angular position 90 of the axis of the propeller about the axis of the shaft.

100 3. A propeller, comprising three concentrically arranged sections, each of which is provided with a plurality of helically disposed blades, an operating shaft positioned transversely of the axis of the propeller in front of the same, three bevel gears secured to the shaft with two of the gears at one side of the axis of the propeller and the other gear at the opposite side of the axis, and three other bevel gears connected for rotation with the sections and meshed with the gears on the shaft, the second mentioned gears connected with the inner and outer sections being meshed with the two gears at one side of the axis of the propeller, and the gear connected with the middle section being meshed with the gear at the opposite side of the axis.

110 In testimony whereof I have hereunto subscribed my name.

GEORGE S. SARGENT.
